UNITED STATES PATENT OFFICE

2,538,642

THERMOPILE FLAME DETECTOR FOR
COMBUSTION DEVICES

Cecil M. Gardiner and Arne Loft, Schenectady,
N. Y., assignors to General Electric Company,
a corporation of New York

Application August 31, 1949, Serial No. 113,296

4 Claims. (Cl. 136—4)

1

This invention relates to flame detection devices for use in combustion apparatus, particularly to a detector of the thermopile type for signalling the presence or absence of flame in the combustor of a gas turbine powerplant.

Many different arrangements have been considered for indicating the presence of flame in combustion apparatus, including certain thermopile devices. Difficulty has been experienced with the previously known devices due to the fact that they did not work equally well with various fuels. It is of course desirable that many different fuels may be used in a gas turbine combustion chamber, for instance the heavy residual oils known as "bunker C," those more highly refined oils used as Diesel engine fuel, ordinary kerosene, various gasolines, and gaseous fuels such as artificial or natural gases. These fuels have widely varying burning characteristics, and the flames they produce are considerably different in their "radiating power." Since a thermopile flame detector of the type described depends principally on the radiant heat received from the flame, it has been found difficult to build such a detector which will work satisfactorily regardless of the type of fuel used.

Accordingly an object of the present invention is to provide an improved flame detector of the thermopile type which will work well with all types of flame, regardless of the fuel particle size or "radiating power" of the flame.

Another object is to provide a thermopile flame detector having satisfactory rapidity of response, both when flame is initiated and when it is extinguished.

A further object is to provide an improved flame detector having greatly lengthened life, yet being low in manufacturing cost and simple in construction.

Other objects and advantages will be apparent from the following description taken in connection with the accompanying drawings, in which Fig. 1 is a diagrammatic representation of a portion of a gas turbine powerplant showing the arrangement of a flame detector in accordance with the invention; Fig. 2 is a sectional view of the flame detector mounted in proper relation to the gas turbine combustor taken on the plane 2—2 in Fig. 1; Fig. 3 is an end view in elevation of the flame detector; Fig. 4 is an elevation view of the other end of the detector; and Fig. 5 is a sectional view of the end portion of the flame detector taken on the plane 5—5 in Fig. 2.

Referring now more particularly to Fig. 1, a flame detector incorporating the invention is

2

shown mounted in proper position in the combustion system of a gas turbine powerplant, in which a compressor of any suitable type, indicated generally at 1, supplies air at a suitable pressure, for instance 75 lbs. per square inch, gage, through diffusing passages 2 and transition passages 3 to the combustor indicated generally at 4. The combustor includes an outer housing 5 surrounding and spaced from an inner liner 6 assembly 6, which latter defines the combustion space. The liner may be supported from the outer housing by any suitable means, for instance suitable radially extending brackets 7. Substantially closing one end of the liner is an "end dome" 8 which is spaced from the inner surface of the liner 6 to form an annular nozzle for discharging a high velocity jet of cooling air along the inner surface of liner wall 6, as indicated by the arrow 9.

10 For introducing liquid fuel in a finely atomized spray into the end dome 8, a nozzle 10 is provided. This may be of any suitable type, but is preferably as shown in the copending application of B. O. Buckland and D. C. Berkey, Serial No. 62,634, filed November 30, 1948, and assigned to the same assignee as the present application. As will be apparent from Fig. 2 of the drawings, this nozzle is secured to a mounting boss 21 formed on the exterior surface of the outer casing 5, and is adapted to inject a conical spray of atomized fuel particles into the end dome 8, as indicated by the dotted lines 11. For igniting the fuel-air mixture, an electric spark plug 12 is secured to the outer housing wall 5 and projects through the inner liner 6 and end dome 8 so that the electrodes provide a spark gap located approximately in the fuel spray pattern 11. Fuel is supplied to the nozzle 10 through a supply 10a containing a solenoid operated shut-off valve 13. If the nozzle 10 is of the "air-atomizing type" disclosed in the above-mentioned Buckland and Berkey application, atomizing air at a suitable pressure is supplied through conduit 10b. Of course, with gaseous fuels a different style of nozzle, not provided with atomizing air, would be employed.

40 The exact details of the compressor, combustor, fuel nozzle, and other components are not essential to an understanding of the present invention; however, it may be noted that the combustor illustrated is of the general type disclosed in the application of Mr. A. J. Nerad, Serial No. 750,015, filed May 23, 1947. An important characteristic of this type of combustor is that the combustion supporting air is injected through 45 circumferential rows of openings 6a at such

pressure and velocity as to form strong discrete jets which persist all the way to the center of the liner, diametrically opposed jets meeting at the axis of the liner to produce a resultant velocity back towards the dome 8, this reverse circulation being represented by the axial air flow arrows 14.

The flame detector itself, to which the present invention particularly relates, is shown generally at 15. It will be apparent that the detector is secured to the outer housing 5 by any suitable means, for instance two or more mounting bolts 16. The major components of the flame detector are contained within a cylindrical barrel 17 of a length to extend completely across the annular air supply space defined between combustor walls 5, 6, with the extreme end portion of the flame detector located in a circular opening formed in the inner liner of wall 6, as may be seen more clearly in Fig. 2. The outer end portion of the flame detector comprises a cylindrical member 18 adapted to receive a suitable electrical connector plug for coupling the flame detector to a suitable electric amplifier indicated generally at 19. The specific type of amplifier employed is not material to the present invention.

The amplifier is of course supplied with power from a suitable source, and delivers an electrical output, in accordance with the signal received from the flame detector, to an electrical control device for modifying the operation of the power-plant. This may, for instance, take the form of a solenoid-operated valve 13, which is arranged to close and shut off the supply of fuel to the nozzle 10 whenever the flame in the combustor becomes extinguished. It will of course be obvious to those skilled in the art that a signalling or indicating device or other arrangements for modifying in a desired manner the operation of the powerplant may be actuated by the flame detector.

The internal structure of the flame detector 15 is shown more particularly in Fig. 2. It will be seen that the mounting bolts 16 pass through a flange 20 suitably secured, as by welding, to the end of the barrel 17, the bolts 16 being threadedly received in the mounting boss 21 with a suitable gasket 22 between boss 21 and flange 20. The gasket is of course for the purpose of preventing leakage of the high pressure air outwardly around the flame detector. The electrical coupling member 18 is exteriorly threaded to receive an internally threaded member of the electrical connector. Member 18 is also provided with a radially extending flange 23 through which pass four machine screws 24 for securing flange 23 to flange 20.

Pressed, molded, or otherwise secured in the internal bore 18a of the electrical coupling member is an insulating body 25 in which are secured two electrical contact prongs 26. The insulating bushing 25 may be of any suitable type, but is preferably of a high temperature resistant molded plastic material, such as the polystyrene plastic known to the trade as "Amphenol." Obviously other plastic or ceramic insulating materials, such as those well known in the spark-plug art may also be employed. It will be seen from Fig. 2 that the contact prongs 26 project at both ends from the insulating body 25, the upper end being a reduced diameter prong 26a adapted to engage a suitable electrical connector plug received in the bore 18a. Fig. 3 is an end view in elevation showing more clearly the shape of the mounting flanges 20, 23, and the arrangement of the re-

spective threaded fastenings 16, 24 and the electrical contact prongs 26a.

Located in the bore 17a, which extends entirely through the barrel 17 of the flame detector, is 5 a cylindrical insulating member 27 having a cylindrical recess 28 into which the electrical prongs 26 project and a pair of spaced axial holes 29 for accommodating the electrical leads for the thermo-pile, as described hereinafter.

10 For supporting the wires forming the thermopile, a third insulating cylinder member 30 is located near the inner end of the barrel 17. It will be seen in Fig. 2 that the extreme inner barrel end portion 17b has a reduced diameter bore 17c 15 forming a shoulder against which the insulator 30 is located. A locating dowel 30a is secured in the barrel 17 and projects into an axial groove in the outer surface of insulator 30 to prevent accidental rotational displacement thereof. It is to 20 be particularly noted that the bore portion 17c constitutes a protected recess in which the "hot junctions" of the thermopile are located, which is important for a reason noted hereinafter.

A cylindrical spacer member 31 holds the insulators 30, 27 in proper axially spaced relation. 25 This metal spacer 31 is not a solid ring but is divided into two halves, along a longitudinal plane, which can be readily assembled in a radial direction between the insulators 30, 27 so as to 30 inclose the thermocouple wires described hereinafter. It will be obvious from Fig. 2 that the two halves of this spacer member 31 are contained within the bore 17a and are engaged at either end by the insulating bodies.

35 A suitable resilient ring 32, made for instance of a temperature resisting artificial rubber such as the "silicone rubbers" is located between the beveled end surface of the coupling member 18 and the adjacent annular end surface of the insulator 27. 40 It will now be apparent that tightening the four machine screws 24 will force the coupling member 18 inwardly so as to compress the ring 32 to seal the clearance space between the coupling member 18 and the barrel 17. This 45 biasing force exerted by the coupling member 18 will also force the insulating bodies 30, 27 and the spacer halves 31 into their proper assembled location in the bore portion 17a. While they 50 may be made of any suitable materials, in the first engineering samples, the insulators 27 and 30 were machined from blocks of soap-stone. In large scale production these parts might be molded porcelain insulators as used in conventional spark-plug practice.

55 The thermopile proper is arranged as follows. As may be seen in Fig. 5, taken in connection with Figs. 2 and 4, the thermopile consists of a plurality of thermocouples connected in series relation. Each consists of a pair of thermo-electrically dissimilar metals, such as those which have 60 become well known to the trade as "Chromel" (90% Ni, 10% Cr) and "Alumel" (95% Ni, 2% Al, 2% Mn, 1% Si). The Alumel wire segments are the ones indicated at 33 in Figs. 4 and 5, while 65 the Chromel portions are those indicated at 34. These respective wire portions 33, 34 are welded together at 35 to form the "hot junctions" of the thermocouples. It will be observed that the junction 35 is not at the exact center of the bore 17c but is displaced so that unequal lengths of the 70 wires 33, 34 are exposed to the flame in the combustion space. The longer exposed segment 34 is made of Chromel, since that material resists oxidation better than the Alumel. These wire segments 33, 34 pass through spaced parallel rows of

75

axial holes 36, 37 in the insulator 30. At the side of the insulator remote from the hot junctions 35, the wire segments are fused together to form the "cold junctions" 38. The respective end wires of the thermopile assembly are bent as shown in Figs. 2 and 5 to form leads 34a, 33a which are suitably secured as by welding at 39 to connecting wires 40 which pass through the openings 29 in insulator 27 and are in turn secured at 41 to the contact prongs 26.

It is important to note that the "cold junctions" 38 of the thermopile are maintained at the temperature of the combustion air flowing through the annular supply passage between the inner liner 6 and the outer housing 5. To this end, the side portions of the barrel 17 and spacers 31 are provided with large circular openings seen at 42, 42a in Figs. 2 and 5, and by dotted lines in Fig. 4. Since the flow of combustion supporting air in the annular passage between walls 5, 6 is in a substantially axial direction, cooling air flows freely straight through the openings 42, 42a and across the cold junctions 38, as indicated by the aligned airflow arrows 43, 44 in Fig. 5. Thus the cold junctions 38 are maintained very accurately at the temperature of the air supplied to the combustion space.

In order to prevent overheating of the thermopile wires at the opposite side of the insulator 30, a cooling air passage is provided through the insulator. This is in the form of an elongated slot 45 three views of which are shown in Figs. 2, 4, and 5. As indicated by the air flow arrow 46 in Fig. 5, a portion of the combustion air passes through the slot 45 and is discharged in a high velocity jet across the exposed hot portions of the Chromel wires 34. It will be observed that this passage 45 is arranged at an oblique angle to the cooling air flow 43 and produces a jet which is not discharged directly at the hot junctions 35 but onto the Chromel wire portions 34. It has been found that this arrangement gives superior performance, as compared with earlier samples in which an axial hole through the insulator 30 produced a jet which discharged directly onto the hot junctions. With the present arrangement, the hot junctions 35 and the exposed portions of the wires 33 are cooled by the conduction of heat to the air-cooled portions 34. It will also be seen in Fig. 5 that a substantial length of the respective wires 33, 34 is exposed to the comparatively cool combustion supporting air at the cold side of insulator 30, so that any heat traveling by conduction along the wires from the hot side of the insulator 30 will be removed by this cooling air flow before it gets as far as the cold junctions 38.

The operation of the flame detector will be seen from the following. In starting the powerplant, the compressor 1 is caused to rotate by an external starting motor (not shown) until the air supplied to the combustor is of a volume flow and pressure adequate to produce a good air-fuel mixture when liquid fuel is injected through the nozzle 10. Of course the automatic shut-off valve 13 must be provided with some means, for instance the manual operating lever 13a for opening the shut-off valve during the starting cycle when there is no flame in the combustor. With valve 13a open, fuel being supplied through the supply line 10a, and air supplied from compressor 1, the spark plug 12 is energized by a suitable ignition system (not shown), whereupon burning begins.

As long as air under pressure is flowing from the compressor through the supply passage between walls 5, 6 and through the flame detector

as indicated by the arrows 43, 44, 46 in Fig. 5, both the cold junctions 38 and the hot junctions 35 of the thermopile will be maintained at the same temperature, namely that of the combustion supporting fluid. As long as this condition obtains, there is of course no net electrical output from the thermopile. On the other hand, when a flame is present within the liner 6, the hot junctions 35 are strongly heated by direct radiation from the flame. The insulator 30 serves as a radiation shield preventing this radiant energy from reaching the cold junctions 38, which latter continue to be maintained at the temperature of the combustion supporting fluid. There is now a temperature difference between the cold and hot junctions, producing a net electrical output, which output is multiplied by the fact that the thermopile consists of eight thermocouples in series relation. The total net signal is very greatly increased by the amplifier 19, the resulting output of which is adequate to hold the fuel shut-off valve 13 in open position. When the flame is extinguished, the air flowing over the cold junctions and the exposed portions of wires 34 quickly brings both hot and cold junctions to the same temperature, whereupon the electrical signal fails and the valve 13 is caused to close.

It may now be noted that one reason why the cooling air slot 45 is inclined as shown in Fig. 5 is to prevent radiant energy passing directly through this passage and impinging on the cold junctions 38. With the angle of the slot as shown in Fig. 5, coupled with the fact that the cold junctions 38 are offset to the right from the centerline of the flame detector, direct radiation from the flame to the cold junctions is prevented. In other words, the oblique slot arrangement facilitates passage of cooling air in one direction but prevents the passage of radiant heat energy in the opposite direction.

It is to be noted that this flame detector is not responsive to the absolute temperature of the combustion gases but to the difference in temperature between the hot reaction products inside the liner 6 as compared with the cooler combustion supporting air flowing between the walls 5 and 6. This is of considerable importance in a gas turbine powerplant since the range of operation from minimum fuel and air flow to maximum, with the wide variation in ambient temperatures encountered, is such that in certain portions of the operating range the temperature of the combustion air (when there is no flame inside the liner) may actually be higher (by reason of the heat of compression added in the compressor 1) as compared with the temperature of the hot burning gases within the liner in certain other portions of the range of operation. For this reason, merely measuring the absolute temperature of the fluids inside the liner 6 will not give a reliable indication as to whether or not there is flame present. But the temperature difference between the air supplied to the combustor and the fluid within the liner will be a satisfactory indication of the presence of flame, since a temperature rise from the air supply passage to the combustion space will occur only when heat release takes place. Thus this thermopile is basically an electrical instrument for detecting a temperature rise in a fluid flowing through the combustion system, which necessarily accompanies any heat releasing reaction occurring within the liner.

Experience with flame detectors made in accordance with the invention has shown that they are quick and reliable in operation, being capable

of detecting the initiation of flame within the combustor with a time delay of perhaps only 1 or 2 seconds. When combustion ceases within the liner, the time interval required for "dropout" is somewhat longer, perhaps on the order of 3 to 15 seconds. This is due to the fact that it takes a short time for all the burning gases to be blown out of the combustion space by the air which continues to be supplied by reason of the rotational inertia of the compressor 4. A perhaps more important factor is that the liner wall 6, and other interior portions of the combustor may be operating at or near red heat, so that these hot parts continue briefly to radiate heat to the thermopile even though the flame has disappeared. When combustion ceases, these parts are of course rapidly cooled by the air flowing through the combustor but they remain hot long enough to introduce a slight delay in the response of the thermopile.

In this connection, it may be noted that a very substantial improvement in the response of the thermopile is effected by having the hot junctions recessed back into the bore portion 17c so as to be shielded from direct contact with the fluids within the combustion space. Furthermore, the skirt portion 17b of the barrel 17 is cooled by the air flowing around it; therefore this skirt also serves as a radiation shield protecting the hot junctions from energy emitted by hot portions of the combustor after the flame has ceased. This shielding arrangement for the hot junctions 35 is also important in that it prevents raw fuel particles projected by the nozzle from collecting on the wires forming the thermopile. In previous models it had been found that, with the hot junctions more exposed, fuel tended to collect on the wires and then burn there, with consequent overheating of the thermocouple wires and serious shortening of the life of the device. Whereas the previous devices burned out after only about one to ten hours of operation, a sample device made in accordance with the invention appears to have almost indefinite life. Specifically, one unit ran for three hundred hours without any sign of failure or deterioration. At the same time, this improved detector is so simple in mechanical arrangement that it costs only about half as much as previously known devices.

An extremely important advantage of this improved flame detector lies in the fact that it has been found capable of operating equally well with a wide variety of fuels, ranging from extremely heavy liquids such as "bunker C" oil to gaseous fuels such as natural gas, in spite of the widely varying characteristics of the flames produced by these fuels. Thus with the invention it is not necessary to change the flame detectors used when the type of fuel is changed.

While only one specific embodiment of the invention has been described in detail, it will be apparent to those skilled in the art that many modifications in the mechanical arrangement of the detector may be made, and we desire to cover by the appended claims all such changes as fall within the true spirit and scope of the invention.

What we claim as new and desire to secure by Letters Patent of the United States is:

1. In a flame detector for a combustion device, the combination of a cylindrical barrel having a central axial bore, a cylindrical insulating body disposed in said bore and spaced axially from the forward end thereof, said insulating body having first and second transversely spaced rows of axial holes for receiving thermopile wires and

a cooling air slot between said rows of holes, said slot being at an acute angle to the axis of the insulator and having a first end portion opening adjacent the first row of holes at the hot side of the insulator and a second end portion opening adjacent the second row of holes at the cold side of the insulator, the forward extending end portion of the barrel forming a shield restricting the direct impingement on the exposed wires of fluids inside the combustion space and of radiant heat from the hot walls thereof, and an electrical thermopile supported by the insulator and comprising a first set of parallel wires of a metal having comparatively good temperature and corrosion resistance and disposed through said first row of holes, the end portions of the wires at the hot side of the insulator extending transversely across the open end of the cooling air slot and terminating between said slot and the second row of holes, the other ends of said wires at the cold side of the insulator extending a substantial distance axially from the insulator whereby any heat traveling by conduction along the wires from the hot ends thereof is dissipated, the extreme end portions of the wires at the cold side of the insulator extending transversely and terminating between the first row of holes and the cooling slot opening at the cold side of the insulator, a second set of wires of electrothermally dissimilar metal disposed through the second row of holes with transversely extending end portions terminating adjacent the respective ends of said first set of wires, adjacent ends of the respective pairs of dissimilar wires being fused together to form a plurality of thermocouples in electrical series relation, said barrel defining openings for admitting combustion supporting fluid to said central bore at the cold side of the insulator, whereby the cold junctions of the thermocouples are maintained substantially at the temperature of the combustion supporting fluid and a portion of the fluid flowing through said openings is caused to be diverted through said cooling fluid slot and discharged across the hot exposed portions of said first set of wires without directly impinging on the hot junctions of the thermocouples.

2. In a flame detector for a combustion device having walls defining a combustion space and an air supply passage, the combination of a cylindrical barrel having a bore extending entirely therethrough with an annular locating shoulder adjacent but spaced axially from the forward end of the barrel, a first cylindrical insulating body disposed in said bore against the locating shoulder and having first and second transversely spaced rows of axial holes for receiving thermopile wires and a cooling air slot between said rows of holes, said slot being at an acute angle to the axis of the insulator and having a first end portion opening adjacent the first row of holes at the hot side of the insulator and a second end portion opening adjacent the second row of holes at the cold side of the insulator, the extreme end portion of the barrel forming a shield restricting the direct impingement on the exposed wires of fluids inside the combustion space and radiant heat from the hot walls thereof, a second cylindrical insulating body disposed in an intermediate portion of the barrel and axially spaced from the first insulator and having two axial passages communicating with a cylindrical recess at the side of the second insulator remote from the first insulator, a spacer sleeve member located between and having end por-

tions contacting the respective first and second insulators, said spacer sleeve being divided along a longitudinal plane into at least two sections whereby the sections may be assembled in a radial direction into position between said insulators, the intermediate portion of the barrel and spacer sleeve sections defining two diametrically opposed cooling air ports adapted to communicate with the air supply passage of the combustion device whereby comparatively cool combustion supporting fluid is supplied freely to the bore of the barrel at the cold side of the first insulator, a first radially extending mounting flange secured to the cold end portion of the barrel and adapted to be secured to the outer wall of the combustion device with the intermediate portion of the barrel extending through the air supply passage and the extreme hot end of the barrel projecting through an opening in the combustion space wall, an electrical coupling member comprising a hollow cylindrical member with an externally threaded end portion for receiving a coupling sleeve, the other end of the coupling member containing a third insulating cylinder member having two contact prong members each with one end portion extending into said threaded end portion of the coupling member and adapted to be engaged by an electrical connector plug, the other end portion of each prong extending into said recess in the adjacent end of the second insulator, the intermediate portion of the coupling member forming a radially extending flange adapted to be secured to said first mounting flange, the adjacent circumferential portions of the second insulator, coupling cylinder member, and barrel bore defining an annular recess, a resilient sealing ring disposed in said annular recess, fastening means for drawing said second flange on the coupling cylinder member tightly against said first mounting flange whereby the first and second insulators and the spacer sleeve are secured in the barrel and the resilient ring is compressed into sealing engagement with the second insulator coupling member and barrel to prevent fluid leakage therebetween, and a thermopile supported by the first insulator and comprising a first set of parallel wires of a metal having comparatively good temperature and corrosion resistance and disposed through the first row of holes in the first insulator, the end portions of the wires at the hot side of the insulator extending transversely across the open end of the cooling air slot and terminating between the cooling slot opening and the second row of holes, the other ends of said wires at the cold side of the insulator extending a substantial distance axially from the insulator whereby any heat travelling by conduction along the wires from the hot ends thereof is dissipated, the extreme end portions of the wires at the cold side of the insulator extending transversely and terminating between the first row of holes and the cooling slot opening at the cold side of the insulator, a second set of wires of electro-thermally dissimilar metal disposed through the second row of holes with transversely extending end portions terminating adjacent the respective ends of said first set of wires, adjacent ends of the respective pairs of dissimilar wires being fused together to form a plurality of thermocouples in series relation, and a pair of lead wire members disposed through the axial holes in the second insulator and having end portions fused to the respective free ends of the dissimilar wire sets and

to the ends of said contact prongs in the recess in the second insulator.

3. In a flame detector for a combustion device, the combination of a hollow cylindrical barrel member, a cylindrical insulating body disposed in the barrel and spaced axially from the forward end thereof, said insulating body having a cooling air slot extending axially therethrough at an acute angle to the axis of the insulator, the forward extending end portion of the barrel forming a shield adapted to restrict the direct impingement on the exposed wires of fluids in the combustion space and of radiant heat from the hot walls of the chamber, and an electrical thermopile comprising a first set of parallel wires of a metal having comparatively good temperature and corrosion resistance disposed through the insulating body in a transverse row adjacent one end opening of the cooling air slot, the end portions of said wires at the hot side of the insulator extending transversely across the adjacent open end of the cooling slot, the other ends of the wires at the cold side of the insulator extending a substantial distance axially from the insulator whereby any heat travelling by conduction along the wires from the hot ends thereof is dissipated, a second set of wires of electro-thermally dissimilar metal disposed through the insulator in a transverse row parallel to and spaced from said first row of wires and having transversely extending end portions terminating adjacent the respective ends of the first set of wires, adjacent ends of the respective pairs of dissimilar wires being fused together to form a plurality of thermocouples in electrical series relation, said barrel having two diametrically opposed openings for passing a comparatively cool combustion supporting fluid transversely through the barrel and over the cold junctions of the thermocouples whereby the latter are maintained substantially at the temperature of the combustion-supporting fluid while a portion of the fluid flowing through said openings is caused to be diverted through the cooling fluid slot and discharged across the hot exposed portions of said first set of wires without directly impinging on the hot junctions of the thermocouples.

4. A flame detector for a combustion device comprising a hollow cylindrical barrel, a cylindrical insulating body disposed in the barrel and spaced axially from the forward end thereof, said insulating body having a cooling fluid slot extending axially therethrough, the forward extending end portion of the barrel forming a shield restricting the direct access of the fluids inside the combustion space and the impingement of radiant heat from the hot walls of the chamber, and an electrical thermopile comprising a first set of wires of a metal having comparatively good temperature and corrosion resistance disposed through the insulating body adjacent one end opening of the cooling slot, the end portions of said wires at the hot side of the insulator being disposed within the sheltered recess defined by said shield and extending transversely across the adjacent open end of the cooling slot, the other ends of the wires at the cold side of the insulator extending a substantial distance axially from the insulator whereby any heat traveling by conduction along the wires from the hot ends thereof is dissipated, a second set of wires of electro-thermally dissimilar metal disposed through the insulator and having transversely extending end portions terminating

adjacent the respective ends of the first set of wires, adjacent ends of the respective pairs of wires being fused together to form a plurality of thermocouples in electrical series relation, said barrel having diametrically opposed openings for passing comparatively cool combustion-supporting fluid transversely through the barrel and over the cold junctions of the thermocouples whereby the latter are maintained substantially at the temperature of the combustion-supporting fluid while a portion of said fluid is diverted through the cooling slot and discharged across 10 the hot exposed portions of said first set of wires, the hot junctions of the thermocouples being spaced transversely from the jet of fluid discharged by said cooling slot whereby the cool-

ing fluid does not impinge directly on the hot junctions. 5
